UNITED STATES PATENT OFFICE.

CHARLES VOGEL, OF FORT LEE, NEW JERSEY.

GRINDING-MACHINE FOR FILE-BLANKS.

SPECIFICATION forming part of Letters Patent No. 228,574, dated June 8, 1880.

Application filed January 7, 1880.

To all whom it may concern:

Be it known that I, CHARLES VOGEL, of Fort Lee, in the county of Bergen and State of New Jersey, have invented an Improved 5 Grinding-Machine for File-Blanks, &c., of which the following is a specification.

File-blanks are usually of different thickness throughout the length, the outer end or point being the thinnest. Sometimes the metal is 10 a true taper, the surfaces being planes that are the closest together at the point, and in other instances the surfaces are slightly convex.

Attempts to grind file-blanks by machinery are attended with difficulty, in consequence of 15 the tapering form.

My machine is made for grinding articles such as file-blanks with great uniformity and rapidity, regardless of the amount of the taper that is given to the blank in the forging operation.

I make use of a revolving slab of emery, or similar material, secured to a metal disk, and the file-blank is moved in the direction of the radius of the slab, and the file-blank is supported by a fence and moved by the action of rollers. These rollers and a stationary bed on 25 which the file-blank is laid serve to present the file correctly to the action of the revolving grinding-slab, and the feed-rollers accommodate themselves to the taper of the file-blank, and cause the grinding to progress regularly by applying the proper relative pressure to the portion of the blank that rests upon the table and to the portion against which the grinding-slab acts.

In the drawings, Figure 1 is a plan view of the machine below the line $y-y$. Fig. 2 is a side view. Fig. 3 is a front elevation of the lower end of the shaft of the revolving slab and its supporting-rest. Fig. 4 is a section at the line $x-x$, showing the links for the feed-rollers, and Fig. 5 is an elevation of the machine with the bed in section.

a is a base, and a' a standard, and b is a bed supported upon the standard, and formed with or connected to the ring b' .

Upon the face of the standard a' is a frame, c , having journal-boxes 2 and 3 for the shaft d , which carries at its upper end the metal 50 disk f and grinding-slab e , attached thereto.

The frame c is connected by V-slides to the standard a' , so that it is held in position; but it can be raised or lowered vertically to bring the grinding-surface at the proper level with the bed b and ring b' , the screw 4, passing 55 through the arm 5 of the frame c , serving to adjust and sustain the frame and grinding-slab in the proper position.

A belt to a pulley, d' , upon the shaft d serves to revolve the shaft d and grinding-slab e at 60 the proper speed.

The grinding-slab is, by preference, formed of a flat ring of emery upon the surface of the disk f , so that the same may be easily replaced when worn out.

Upon the bed b and ring b' there is a fence or support, h , against the edge of which the file-blank lies as placed upon the bed b . This fence, is in such a position that the file-blank will be radial to the disk, or nearly so, and 70 such file-blank is to be moved endwise as it is ground, commencing at or near the point.

The rollers $l m$ are preferably made with an elastic covering, such as india-rubber upon metallic rollers, and such rollers revolve upon 75 shafts or gudgeons 7 and 8, that are received in and supported by the pairs of links $o o'$ and $r r'$, the ends of which links swing upon the shaft 9. The motive power that moves the rollers $l m$ is applied to the pulley p , and a 80 pinion on the shaft of said pulley rotates the wheel s and its shaft 12, and also the wheel t and its shaft 9, and at the other end of the shaft 9 there is a small gear-wheel, 15, that gears into the pinions 17 and 18, that are 85 formed with or connected to the rollers $l m$.

The links $o o'$ and $r r'$, that sustain the shafts 7 and 8, allow the rollers $l m$ to rise or fall, and at the same time the wheels are kept in gear, because the power is derived from the 90 same shaft that forms the pivot for the links to swing upon, and there are stop-screws 19, (see Fig. 4,) that limit the downward movement of the links, and prevent the rollers $l m$ coming into contact with the bed b or grinding-slab e .

The lever v is pivoted upon the frame v' , and has links 20, 21, and 22. The lower ends of the latter are pivoted to the links $o o'$, so that by depressing the handle of the lever the 100

rollers l m can be lifted for the insertion of a file-blank beneath them, and the weight 24 will, when the machine is in use, act through the links and press the rollers upon the file-blank with the proper force to keep the same down upon the bed and the grinding-slab, respectively, and, in order to regulate the relative pressure, the pivots that connect the links o' and 22 and o and 21 are movable in slots in o o' , so that the pressure acts with more or less leverage, according to the distance that the pivot is from the roller.

The frame v' can be swung upon the shaft 12 as the center, so as to move the rollers toward or from the center of the revolving slab, and thus adjust them relatively to the place where the grinding is being performed and the bed on which the file-blank rests.

The arch-piece 26, which is slotted, serves to sustain the frame v' in its position by a bolt passing through the slot.

At the end of the shaft 12 there is a wheel, 30, and the shaft 12 also forms a fulcrum for the lever 31, and 32 is a gear-wheel, and 33 a roller (shown by dotted lines in Fig. 2) at the short end of the lever, that is revolved by the gearing and passes up into a mortise in the bed b , so as to press against the under side of the file-blank as it lies upon the bed.

30 The weight 34 is movable on the lever 31, and it is not intended that the leverage shall be sufficient to cause the roller 33 to lift the file-blank from the bed, but only that it shall lessen the friction of the same upon the bed 35 and prevent the blank stopping as it is moved along endwise over the grinding ring e by the rollers l , m , and 33.

As the grinding progresses the blank running against the fence h is guided by the bed, 40 and the two upper rollers, l m , press the blank toward the bed, and if the blank is flat the grinding will make the surface level; but the rollers are free to rise as the thicker portion of the file-blank passes beneath them. If the 45 file-blank is slightly convex the grinding will be true, but the convexity will remain.

If the lower roller, 33, has a covering of india-rubber it may be used to feed the file-blank along if a suitable spring is used to hold the file-blank down to the bed.

50

In my machine the rollers will tend to keep the body of the file-blank flat upon the bed. Hence if there is any inequality or twist in the end of the file-blank, where it has been forged down thinner, the grinding will remove such 55 inequality.

I claim as my invention—

1. The combination, in a file-grinding machine, of the rollers l m , gears 15 17 18, links o o' r r' , shafts 7, 8, and 9, lever v , links 20 21 60 22, connected adjustably to the links o o' , and the stop-screws 19, substantially as and for the purposes set forth.

2. The combination, in a file-grinding machine, of a flat revolving grinding-ring adjustable vertically, a bed, b , ring b' around the grinding-ring, and a fence, h , attached to the bed and ring b' , respectively, and against which the file is moved in grinding, substantially as set forth.

70 3. The combination, in a file-grinding machine, of the rollers l m and the gearing for the same, the adjustable frame v' , for allowing the rollers to be moved toward or from the grinding-slab, the levers and links for applying pressure to the rollers, and the stop-screws 19, substantially as set forth.

4. The combination, with the bed b , of a weighted lever, 31, a roller, 33, upon the short arm of the lever acting within a mortise in the bed to move the file-blank or other article resting upon the bed, and gearing connecting the roller to the actuating-shaft 12, which shaft also forms the fulcrum for the lever, substantially as set forth.

85

Signed by me this 2d day of January, A. D. 1880.

CHARLES VOGEL.
